SPRINKLER HEAD STABILIZER AND PROTECTOR

Peter J. Sbicca, 2895 Lorain Road,
San Marino, Calif. 91108

Filed Dec. 12, 1973, Ser. No. 423,939

Term of patent 14 years

Int. Cl. D23—01

U.S. Cl. D23—7

FIG. 1.

FIG. 2.

FIG. 5.

FIG. 3.

FIG. 4.

FIG. 6.

FIG. 1 is a top plan view of a sprinkler head stabilizer and protector embodying my new design;

FIG. 2 is a side elevational view thereof;

FIG. 3 is a bottom plan view thereof;

FIG. 4 is a fragmentary cross-sectional view taken along line 3-3 on FIG. 2;

FIG. 5 is a top plan view of a modified form of the sprinkler head stabilizer and protector shown in FIG. 1; and

FIG. 6 is a fragmentary cross-sectional view taken along line 6-6 on FIG. 5.

I claim:

The ornamental design for a sprinkler head stabilizer and protector, as shown and described.
